United States Patent Office

Des. 178,961
Patented Oct. 16, 1956

178,961

STOPPER OR SIMILAR ARTICLE

George T. James, Pasadena, Calif., assignor to Gladding,
McBean & Co., Los Angeles, Calif., a corporation of
California

Application July 9, 1954, Serial No. 31,362

Term of patent 14 years

(Cl. D58—10)

Fig. 1.

Fig. 2.

Fig. 1 is a top perspective view of a stopper or similar article embodying my new design.

Fig. 2 is a vertical, cross-sectional view taken through the center thereof, on a reduced scale.

I claim:

The ornamental design for a stopper or similar article, substantially as shown.
